UNITED STATES PATENT OFFICE.

HERMANN MÜLLER, OF NUERMBERG, GERMANY.

HIGH-TENSION SWITCH.

SPECIFICATION forming part of Letters Patent No. 595,887, dated December 21, 1897.

Application filed June 2, 1897. Serial No. 643,216. (No model.)

To all whom it may concern:

Be it known that I, HERMANN MÜLLER, a citizen of the Empire of Germany, residing in Nuremberg, in the Kingdom of Bavaria, 5 in the Empire of Germany, have invented certain new and useful Improvements in High-Tension Switches, of which the following is a specification.

This invention relates to certain improvements in high-tension switches in which the oxidation of the contacting parts and the consequent objectionable insulation of these parts can be to a great extent prevented and neutralized and a high-tension switch of superior properties and durability is obtained.

It has been found in lightning-protectors that the passage of a spark of a high-tension current can be readily prevented when two conditions are present, as follows: First, when 10 the contacting parts by which the circuit is closed are formed of an easily-oxidizing metal and the oxid of which is a good non-conductor of electricity—that is to say, composed of a non-arching metal; second, when the distance between the contacting parts is very 15 small, as when the distances between the contacting parts are large, in consequence of the greater heating and the consequent evaporation of the metal, an arc may be formed as 20 described by Wurts in his papers. It was therefore proposed to form the contacting parts of balls or rollers arranged in a row, so that when these balls or rollers are pressed together the circuit is closed, while the circuit 25 is interrupted by separating the balls or rollers or the formation of small spaces between the contacting parts when the pressure on the parts is removed. The small sparks which are formed on the separation of the 30 contacting parts are, in consequence of the oxid, quickly extinguished, as before described. The insulating property of the resulting oxid, however, has the disadvantage that after a comparatively short use of such 35 a switch the circuit cannot be entirely and reliably closed.

The object of my invention, therefore, is to obviate these objections and provide a switch for high-tension currents, in which the 40 objectionable interference of the oxidation of the contacting parts is avoided; and the invention consists of a high-tension switch

composed of a series of roller-shaped contact-pieces arranged in a row, which are made of easily-oxidizing non-arching metal and of a mechanism by which said rollers can be either 55 pressed together or separated from each other in such a manner that by the closing and opening, respectively, of the circuit a turning motion is imparted to said contact-pieces, as 60 will be fully described hereinafter, and finally pointed out in the claims.

In the accompanying drawings, Figure 1 represents a front elevation, and Fig. 2 is a side elevation, of my improved switch for 65 high-tension currents.

Similar letters of reference indicate corresponding parts.

Referring to the drawings, A represents a plate of non-conducting material on which a series of contact-pieces formed in the shape of rollers *a* are arranged in line with each other. The roller-shaped contact-pieces *a* are made to turn easily on their axes, which are mounted on flat springs *b*. The contact- 70 rollers *a* are divided into two groups, an upper and lower, and between said groups eccentric cams *d* are arranged, which are mounted on a shaft *d'*, that is turned by a hand-lever *d''*. The eccentric cams *d* are in contact 75 with the adjacent rollers of each group and produce the pressing together of the contact-rollers of each group when the hand-lever *d''* is moved in the direction of the arrows into 80 position for closing the circuit. When the hand-lever is returned into its normal position, the eccentric cams release the rollers and produce the interruption of the contact of the same. The contact-rollers *a* at the end 85 of each group are mounted on heavy metallic plates *e*, so that they can change their position but little, even when the intermediate 90 rollers are forced in contact with each other.

It is obvious from a cursory examination of the construction described that during the closing as well as during the opening of the circuit a turning motion is imparted to all the contact-rollers *a* up to *a'*. As, furthermore, the friction of the different contact-rollers on their shafts differs slightly it follows that 95 after each use of the switch new contact portions of the cylindrical surface of the rollers are placed adjacent to each other, so that thereby a greater durability and usefulness 100

of the switch is obtained. Another advantage is that by the friction of the rollers any oxid that is formed on the same is removed by the friction of the rollers with each other. 5 Owing to these two facts the switch can be used for a much greater length of time without requiring repairs, which is of considerable importance in high-tension switches, owing to the danger connected with the touching of their parts.

10 The hereinbefore-described disposition of the rollers can also be used for commutators. With electric currents of great strength it is preferable to arrange the switch in a shunt-circuit of an ordinary cut-out, so that a connection with comparatively small resistance for the passage of the current is obtained.

15 Having thus described my invention, I claim as new and desire to secure by Letters 20 Patent—

1. A switch for high-tension currents, consisting of groups of contact-rollers made from easily-oxidizable non-arching metal, said

groups of rollers being mounted on spring-arms, each roller being normally out of contact with the others, and means for forcing the rollers into contact with each other, while simultaneously a turning motion is imparted to the same, substantially as set forth. 25

2. A switch for high-tension currents, 30 formed of a group of contact-rollers made of easily-oxidizable non-arching metal, said rollers being mounted on spring-arms and normally out of contact with each other, intermediate eccentric cams operated by a hand-lever and adapted to place the contact-rollers of each group in contact with each other, substantially as set forth. 35

In testimony that I claim the foregoing as my invention I have signed my name in presence of two subscribing witnesses.

HERMANN MÜLLER.
